FIG-1

FIG-2

FIG. 1 is a perspective view of a differential transmission unit, embodying my new design;

FIG. 2 is an elevation as seen from the side opposite to that disclosed in FIG. 1, the shaft member being broken away for convenience of illustration only;

FIG. 3 is a top plan view thereof;

FIG. 4 is an elevational view of the front end of the design shown in FIG. 1; and

FIG. 5 is an elevational view of the rear end of the design shown in FIG. 1.

I claim:

The ornamental design for a differential transmission unit, substantially as shown and described.
